Des. 193,932
Patented Oct. 30, 1962

193,932

PRINTER CONSOLE

Rae F. Tankard, Binghamton, N.Y., assignor to International Business Machines Corporation, New York, N.Y., a corporation of New York

Filed May 23, 1961, Ser. No. 65,294

Term of patent 14 years

(Cl. D26—5)

FIG. 1

FIG. 2

FIG. 3

FIG. 4

FIG. 5

FIG. 6

FIGURE 1 is a front perspective view of a printer console embodying my new design;

FIGURE 2 is a side elevational view;

FIGURE 3 is another side elevational view showing the side opposite that shown in FIGURE 2;

FIGURE 4 is a top plan view;

FIGURE 5 is a rear elevational view, and

FIGURE 6 is a rear perspective view of the printer console shown in the preceding five figures.

The essential features of my design reside in the portions shown in solid lines in the drawing.

I claim:

The ornamental design for a printer console, as shown and described.
